Patented May 8, 1973

226,851

BATHTUB AND SHOWER ENCLOSURE COMBINATION

Stanley F. Korol, Mansfield, Ohio, assignor to Borg-Warner Corporation, Chicago, Ill.

Filed Feb. 28, 1972, Ser. No. 230,171

Term of patent 14 years

Int. Cl. D23—02

U.S. Cl. D23—49

Fig. 1

Fig. 2

Fig. 3

FIG. 1 is a perspective view of a bathtub and shower enclosure embodying my new design;

FIG. 2 is a cross sectional view of the wall portion thereof taken on line 2—2 of FIG. 1; and

FIG. 3 is a cross sectional view of the tub portion thereof taken on line 3—3 of FIG. 1.

It is to be understood that the pattern is complete in the panels where indicated.

I claim:

The ornamental design for a bathtub and shower enclosure combination, as shown and described.
